DESIGN FOR AN ORNAMENTAL PLATE FOR A CASKET OR ANALOGOUS ARTICLE

Raymond Larson, Chicago, Ill., assignor to Central Metallic Casket Co., Chicago, Ill., a corporation of Illinois

Application August 17, 1935, Serial No. 58,184

Term of patent 7 years

To all whom it may concern:

Be it known that I, Raymond Larson, a citizen of the United States, residing at 2207 North Lamon Avenue, Chicago, in the county of Cook and State of Illinois, have invented a new, original, and ornamental Design for an Ornamental Plate for a Casket or Analogous Article, of which the following is a specification, reference being had to the accompanying drawing, forming part thereof.

Fig. 1 is a side elevational view of an ornamental plate for a casket or analogous article embodying my new design;

Fig. 2 is an end elevational view of the same; and

Fig. 3 is a top plan view of the same.

I claim:

The ornamental design for an ornamental plate for a casket or analogous article as shown.

RAYMOND LARSON.
